UNITED STATES PATENT OFFICE.

LAWRENCE B. JENCKES AND JOHN G. SODERBERG, OF WORCESTER, MASSACHUSETTS,
ASSIGNORS TO CROMPTON & KNOWLES LOOM WORKS, OF WORCESTER, MASSACHUSETTS,
A CORPORATION OF MASSACHUSETTS.

TUBE FRAME FOR MOQUETTE LOOMS.

Application filed November 28, 1921. Serial No. 518,132.

To all whom it may concern:

Be it known that we, LAWRENCE B. JENCKES and JOHN G. SODERBERG, both citizens of the United States, residing at Worcester, in the county of Worcester and State of Massachusetts, have invented a new and useful Tube Frame for Moquette Looms, of which the following is a specification.

This invention relates to the tube frames which are used in large numbers in moquette looms. Present conditions demand that the frames be of much greater length than has been heretofore customary. It is essential that the longitudinal alignment of the tube frames be accurately preserved, particularly during the delivery of yarn therefrom, and it is the object of our invention to provide means for stiffening the tube frames and increasing their resistance to vertical deflection.

Our invention further relates to arrangements and combinations of parts which will be hereinafter described and more particularly pointed out in the appended claims.

Preferred forms of our invention are shown in the drawings in which:

Fig. 1 is a side elevation of one of our improved tube frames;

Fig. 2 is a partial side elevation of the stiffening members for the frame shown in Fig. 1;

Figs. 3 and 4 are sectional views taken along the lines 3—3 and 4—4 in Fig. 1;

Fig. 5 is a partial side elevation of a modification;

Fig. 6 is a bottom view thereof;

Fig. 7 is a sectional view taken along the line 7—7 in Fig. 5.

Referring to the drawings, we have shown a tube frame comprising a hollow rectangular bar 10, to the side of which the yarn tubes 11 are secured in the usual manner. Bearing brackets 12 are mounted on the ends of the bar 10, and intermediate bearings 13 are secured to the upper side thereof, these bearings supporting one or more yarn spools 14. The general arrangement of the parts thus far described is shown in the prior patent to Hutchins No. 1,065,871 issued June 24, 1913, to which reference is made for a more detailed description.

The brackets 12 may be provided with inwardly extending plates or arms 15 re-

ceived within the ends of the hollow bar 10. These arms fit closely within the bar and may be secured thereto by screws 16. It is desirable to use flat or counter-sunk head screws, and in order to provide sufficient thickness to receive the heads of such screws, we form depressed portions 17 in the arms 15, through which holes may be threaded to receive the screws 16. It is thus possible to thread the full thickness of the arms of plates 15.

As previously stated, it is very essential that the tube frame and the ends of the tubes 11 shall be held in accurate alignment during the delivery of yarn therefrom. For this purpose we provide stiffening members 18 disposed longitudinally within the bar 10. These stiffening members are commonly in the form of long wooden wedges reversely disposed within the hollow bar. The wedges are inserted from the ends to the bar, and are driven toward each other until they are firmly seated within the bar, after which a screw 19 may be inserted to prevent their displacement. This screw may also serve as one of the fastenings for an intermediate bearing 13.

In Figs. 5, 6 and 7 we have shown a slight modification in which the wedge-shaped stiffening members 20 engage the sides of the bar 10 instead of the top and bottom thereof. One or more screws 21 extend through the side of the bar and act to hold the members in place.

Having thus described our invention, the advantages thereof will be readily apparent. The stiffening members 18 or 20 may be made of pine or other light wood and add very little to the weight of the frame. They produce a marked effect, however, upon the stiffness of the tube frames and they also act to reduce the vibration thereof.

It will be further evident that changes and modifications may be made in our construction within the spirit and scope of our invention as set forth in the claims, and we do not wish to be otherwise limited to the details herein disclosed, but what we claim is:

1. A tube frame for a moquette loom comprising a hollow rectangular bar to which yarn tubes are secured, means to support yarn spools thereon, and means to stiffen

said bar, said means comprising longitudinally extending reversed wedge-like members firmly seated therein.

2. A tube frame for a moquette loom comprising a hollow rectangular bar to which yarn tubes are secured, means to support yarn spools thereon, and means to stiffen said bar, said means comprising longitudinally extending tapered wood strips reversely disposed in said bar.

3. A tube frame for a moquette loom comprising a hollow rectangular bar to which yarn tubes are secured, means to support yarn spools thereon, and means to stiffen said bar, said means comprising longitudinally extending reversed wedge-like members firmly seated therein, and means to hold said strips from displacement.

4. A tube frame for a moquette loom comprising a hollow rectangular bar to which

yarn tubes are secured, means to support yarn spools thereon, and means to stiffen said bar, said means comprising longitudinally extending reversed wedge-like members firmly seated therein, and firmly engaging the upper and lower walls of said bar.

5. In a tube frame, a hollow bar, a spool-holding bracket having arms extending into said bar, said arms each having a depressed portion and having also a threaded hole in said depressed portion, and screws extending through the walls of said bar and threaded in said openings to secure said bracket in position.

In testimony whereof we have hereunto affixed our signatures.

LAWRENCE B. JENCKES.
JOHN G. SODERBERG.
